(57) **CLAIM**

The ornamental design for a base station for security camera as shown and described.

DESCRIPTION

FIG. 1.1 is a bottom plan view of a base station for security camera showing our new design;

FIG. 1.2 is a front elevational view thereof;

FIG. 1.3 is a front, top, and right side perspective view thereof;

FIG. 1.4 is a left side elevational view thereof;

FIG. 1.5 is a rear elevational viewtop plan view thereof;

FIG. 1.6 is a right side elevational view thereof; and

FIG. 1.7 is a top plan view thereof.

The broken lines in the drawings depict portions of the base station for security camera that form no part of the claimed design.
